(57) **CLAIM**

I claim the ornamental design for footwear, as shown and described.

DESCRIPTION

FIG. 1 is a side, top perspective view of footwear; and, FIG. 2 is a side elevation view of the footwear of FIG. 1. The ornamental design that is claimed is shown in solid lines in the drawings. The broken (dashed) lines shown in FIGS. 1 through 2 are included for the purpose of illustrating environmental elements only and form no part of the claimed design.
